UNITED STATES PATENT OFFICE.

ABRAM E. SMITH, OF BROOKLYN, NEW YORK.

DISCHARGE APPLIANCE FOR RAILROAD TANK-CARS.

1,136,375.

Specification of Letters Patent. Patented Apr. 20, 1915.

Application filed November 29, 1910. Serial No. 594,630.

To all whom it may concern:

Be it known that I, ABRAM E. SMITH, a citizen of the United States, residing at Brooklyn, in the county of Kings and State of New York, have invented certain new and useful Improvements in Discharge Appliances for Railroad Tank-Cars, of which the following is a specification.

This invention relates to the appliances which are used at the bottoms of the tanks of railroad tank cars for discharging the tanks' contents, when desired. A set of such appliances for a tank car includes a discharge nozzle which is permanently secured to the outside of the tank and a lift valve which rests, when closed, on a seat at the upper end of the nozzle and best below the tank floor; so as to empty the tank completely when the valve is raised. In case of accident to the car these nozzles are apt to be bent or broken; and with the valve arrangement heretofore in most common use such bending or breaking of the nozzle is apt to dislodge the valve from its seat sufficiently to allow the contents of the tank to escape with more or less rapidity. Should the tank contain oil or other inflammable liquid, especially a very inflammable liquid like gasolene, the direct loss by the accident may be even surpassed by loss from fire consequent on the escape of the contents of the tank.

In the accompanying drawings, Figure 1 is a partial view in vertical section and elevation of the tank of a railroad tank car provided with the appliances of the present invention, in what is considered the best form of the same, the valve being raised for discharging; Fig. 2 is a plan view of the valve; Fig. 3 is a side view of the same; Fig. 4 is a side view of the valve with part of its operation rod; Fig. 5 is a plan view of the discharge nozzle; and Fig. 6 is a vertical section of the same in a plane at right angles to that of Fig. 1.

The discharge nozzle *a* provided at top with an attaching flange *b* and a seat *c* for the valve is secured by rivets to the bottom of the tank *d* below the discharge opening *e* in the tank bottom of somewhat larger dimensions in all directions than the valve seat *c* and valve *f*; so that this last may pass through said opening in order to rest on its seat *c*. The valve *f* is provided on top with ears *g* by which it is secured to the lower end of the valve operation rod *h* (Fig. 4). This

rod *h* can be guided and operated in any suitable way, it being common to provide a cam for raising and a spring for holding down the corresponding rod and valve in railroad tank cars.

The valve *f* is provided underneath with a stout but very shallow guide portion *k* and with a readily flexible or breakable guide pin *m* projecting below the same. The guide pin *m* may be made of soft steel or other metal which can be readily bent. The portion *k* is guided by the walls of the discharge nozzle *a*; and the pin *m* is guided by the walls of a small hole *n* in the guide *p* inside of said nozzle.

Below the guide *p* is a groove *q* for weakening the resistance to breakage of the nozzle at that point as compared with its resistance above said groove. It is considered best also to extend the guide *p* across the nozzle bore so that it will act as a brace inside the nozzle. The depth of the guide portion *k* on the valve would best not exceed the thickness of the attaching flange *b* of the discharge nozzle; so as to be removed from pressure tending to dislodge the valve, in case the discharge nozzle should be broken off even as high up as the under side of said flange. The pin *m* is best made of such small resistance that it can be bent or broken without dislodging the valve *f* from its seat *c*. The fit of the guide portion *k* within the nozzle *a* aids materially in holding the valve firmly in its seat; but as it must be lifted clear of the nozzle when the valve is raised, the pin *m* is provided to guide the valve in closing. As shown, the guide pin *m* is of smaller diameter than the valve operating rod *h*, and smaller than the rivets by which (as shown) the attaching flange *b* of the nozzle *a* is secured to the tank *d*. It may well be made of steel or wrought iron and be about half an inch in diameter.

I claim as my invention or discovery:

1. In combination with the tank of a tank car, which tank has a discharge opening at its bottom; a discharge nozzle secured to the bottom of the tank, registering with the discharge opening and provided with a breaking point below the discharge opening of the tank; a guide within the nozzle extending across it; a valve for opening and closing the discharge opening; and a pin carried by said valve, passing through an opening in the guide and extending below the breaking point of the nozzle when the

valve is seated and of a resistance which permits of its being bent without unseating the valve.

2. In combination with the tank of a tank car which tank has a discharge opening in its bottom; a discharge nozzle secured to the bottom of the tank and registering with the discharge opening; a guide extending across the nozzle; a valve for opening and closing the discharge opening; and a pin projecting from the valve and through the guide and capable of being bent without unseating the valve.

3. In combination, a tank car having a discharge opening at its bottom; a discharge nozzle secured to the tank bottom and registering with said opening, said nozzle having a breaking point; a valve for said opening and having its seat above said breaking point; means for moving said valve to and from its seat; and means connected with the

valve, located within the nozzle and constructed upon breaking of the nozzle to prevent dislodgment of the valve from its seat.

4. In combination with the tank of a tank car having a discharge opening at its bottom; a valve within the tank for opening and closing said opening; means within the tank for operating said valve; a depending discharge nozzle secured to the tank below the valve and provided with a breaking point; and means comprising a pin located within the nozzle and carried by the valve which, when the nozzle is broken, acts to hold the valve seated.

In testimony whereof I affix my signature in presence of two witnesses.

ABRAM E. SMITH.
